UNITED STATES PATENT OFFICE.

JAMES D. CAVANAUGH, OF LEBANON, ASSIGNOR TO NATHAN S. ALTHOUSE
AND JAMES H. KNOLL, OF READING, PENNSYLVANIA.

WASHING-MACHINE.

SPECIFICATION forming part of Letters Patent No. 527,360, dated October 9, 1894.

Application filed January 23, 1894. Serial No. 497,795. (No model.)

To all whom it may concern:

Be it known that I, JAMES D. CAVANAUGH, a citizen of the United States, residing at Lebanon, in the county of Lebanon and State of Pennsylvania, have invented a new and useful Washing-Machine, of which the following is a specification.

The invention relates to improvements in washing machines.

10 The object of the present invention is to improve the construction of washing machines, and to provide a simple and effective one, which will be capable of rapidly and thoroughly washing clothes or other fabrics, and 15 in which the pressure on the clothes during the operation of washing may be readily regulated.

The invention consists in the construction and novel combination and arrangement of 20 parts hereinafter fully described, illustrated in the accompanying drawings and pointed out in the claims hereto appended.

In the drawings—Figure 1 is a perspective view of a washing machine constructed in accordance with this invention. Fig. 2 is a vertical longitudinal sectional view of the same. Fig. 3 is a transverse sectional view of the washing machine. Fig. 4 is a detail view of the gearing.

25 Like numerals of reference indicate corresponding parts in all the figures of the drawings.

1 designates an oscillating washing machine body, journaled on a supporting frame or stand 2, and provided with an interior rubbing surface 3; and 4 designates a reversely oscillating approximately semi-cylindrical rubber, which is provided with an exterior rubbing surface 5. The body 1 has a curved 35 bottom and ends to conform to the general configuration of the rubber 4, and clothes or other fabrics to be washed are placed in the body between the rubbing surfaces 3 and 5, and when the body and the rubber are reversely oscillated the clothes are thoroughly rubbed. A semi-cylindrical top or cover 6 is arranged on the body, 1, and is hingedly connected with one side thereof by separable hinge castings 7 and 8.

40 The stand 2 is preferably pyramidal with

opposite inclined legs; and it is provided at the upper ends of the legs, which are secured together, with bearings 9, in which are arranged hollow journals 10 of the body 1. The hollow journals 10 form bearings for extended 55 journals 11 of the rubber 4, whereby the rubber 4 is journaled within the body and is supported by the frame or stand.

On one side of the body is secured a segment 12, which is provided on its upper concave periphery or face with teeth; and a smaller segment 13 depends from and is rigidly secured to one of the extended journals 11. The depending segment 13 is provided at its inner side at its convex face or periphery with teeth; and these two segments mesh with a pinion 14 journaled on a stub shaft 15 of the frame, whereby when the body is oscillated the rubber 4 will be reversely oscillated. The body is provided at one end with a handle 16, by means of which the washing machine is operated.

The extended journals 11 are formed integral with vertically disposed bars 17, which are arranged in grooves or ways 18 of the 75 sides of the oscillating rubber 4, and which are provided with rack bars 19 forming upward extensions of the bars 17, and adapted to be engaged by sliding latches 20 of the oscillating rubber, whereby the distance between the rubbing surfaces 3 and 5 may be varied and the pressure exerted on the clothes during washing may be adjusted. The grooves or ways 18 are arranged on the exterior faces of the sides of the oscillating rubber 4, and the rack portions of the bars 17 extend upward through openings of plates 21, and the latches 20 are mounted on a cross-bar 22, and are arranged at the inner sides of the racks.

It will be seen that the washing machine is 90 simple and comparatively inexpensive in construction, that it is effective in operation, and that it is capable of thoroughly and rapidly washing clothes or other fabrics without liability of injuring them. It will also be seen that the washing machine body and the rubber 4 can be rapidly reversely oscillated at the expenditure of a minimum amount of labor, and that the oscillating rubber is capable of vertical adjustment to vary the distance 95 100

between the rubbing surfaces to accommodate a greater or less quantity of clothes, and to regulate the pressure on the latter.

Changes in the form, proportion and the minor details of construction may be resorted to without departing from the principle or sacrificing any of the advantages of this invention.

What I claim is—

10. 1. In a washing machine, the combination of a supporting frame, an oscillating body journaled on the frame and provided with a tooth segment, an oscillating rubber arranged within the body and having a segment connected with it and provided with teeth arranged opposite those of the segment of the body, and a pinion mounted on the frame and interposed between and meshing with said segments, whereby the body and the rubber are caused to oscillate reversely, substantially as described.
15. 2. In a washing machine, the combination of a supporting frame, an oscillating rubber, an oscillating body journaled on the frame and receiving the rubber, journals supported on the frame and extended through the body and adjustably connected with the rubber, whereby the latter may be raised and lowered, and gearing connected with one of the journals of the rubber and with the body for reversely oscillating the rubber and the body, substantially as described.

3. In a washing machine, the combination of a supporting frame, an oscillating body journaled on the frame, an oscillating rubber arranged within the body and provided with vertical ways, bars arranged in the ways of the rubber and having vertically extending racks and provided with journals extended through the body and arranged in suitable bearings of the frame, and catches mounted on the rubber and arranged to engage the racks to secure the rubber at the desired adjustment, substantially as described.

4. In a washing machine, the combination of a supporting frame, a body provided with hollow journals arranged in suitable bearings of the supporting frame, an oscillating rubber provided with journals extended through the body and arranged within said hollow journals, a segment depending from one of the journals of the rubber and provided at its outer periphery with teeth, a segment secured to the body and provided on its upper face with teeth, and a pinion journaled on the frame and meshing with the segment, substantially as described.

In testimony that I claim the foregoing as my own I have hereto affixed my signature in the presence of two witnesses.

JAMES D. CAVANAUGH.
